UNITED STATES PATENT OFFICE.

HENRY BORN, OF CLEVELAND, OHIO.

GRATE.

SPECIFICATION forming part of Letters Patent No. 364,209, dated June 7, 1887.

Application filed January 14, 1887. Serial No. 224,269. (No model.)

To all whom it may concern:

Be it known that I, HENRY BORN, of Cleveland, in the county of Cuyahoga and State of Ohio, have invented a certain new and Improved Stove or Furnace Grate; and I do hereby declare that the following is a full, clear, and complete description thereof.

My invention relates to grates which may be used in furnaces, stoves, or ranges, which will be hereinafter more particularly described, and pointed out in the claims.

That my invention may be more fully understood, reference will be had to the following specification and accompanying drawings, making part of the same, in which—

Figure 1 is a plan view of the combined grate. Fig. 2 is a central longitudinal section thereof, and Fig. 3 is an end view of Fig. 1.

Like letters of reference refer to like parts in the several views.

In the drawings, A represents the bed, in which is the frame B, Fig. 1, bearing or resting in the lower angular flanges, a, thereof, Fig. 3. Said frame consists of the longitudinal side pieces, b b, and the end and cross pieces c and d, by which are formed the bearings for the front and back grate, C and D. In the front part of the grate the side pieces, b b, are formed with angular projections e, constituting part of the grate-surface. Between them is located the revolving cylindrical grate C, which consists of the end rings, f and g, and connected by the bars i and j with intervening spaces, describing a spiral line of bars and spaces. Between these bars are longitudinal bars or strips K and l, Figs. 1 and 2, for the purpose of adding strength and durability to the structure.

Attached to the rings f and g are arms m and n, which terminate in pivots or journals o p, by means of which the grate C is suspended in the bearings a' and c'. Within the frame B, (in Fig. 2,) extending from the pivot o, is a shaft, o', provided with a ratchet, P, arranged in relation to the pawl P', pivoted to the stove at the end. To the square end of the shaft o' is to be fitted a crank, (not shown,) whereby the grate C can be rotated in the proper direction for discharging the ashes and cinders.

The pawl and ratchet prevent a rotation of 50 the grate C reversely to that indicated by the arrow in Fig. 3, so that on turning the grate C the deposits thereon are always moved backward, owing to the helical formation of the grate-bars i and j.

The pawl is shown in dotted lines, not for the reason of being pivoted to the grate of the furnace or range, (not shown in the drawings,) but to indicate the relative location of the pawl to the ratchet-teeth. In the frame B is located 60 the grate D, pivoted in bearings q' q, respectively in and between the side pieces, b b. The bar r is loosely connected to the bed A and is provided on one end with a roller, s, by means of which the grate is held up against the lug 65 t. Within the slot r' is a guide, r'', attached to the side of the bed A, and which sustains and allows the bar to be withdrawn or moved out, causing the grate D to drop to a position shown by the dotted lines in Fig. 2. On the 70 inward movement of the bar r the grate D is raised up to a horizontal position.

This peculiar construction and arrangement of grates greatly facilitate the obtaining and maintaining a good fire in a furnace or range. 75 For instance, a few turns of the grate C in direction of the arrow will move the fire backward and make room in front for a fresh supply of coals. At the same time the ashes and slack which fall through the bars into the interior of the grate C will be carried toward the ash-pit, which is directly under the grate D, and will be finally discharged into the same through the opening n' in the end of the 80 grate C.

It will be noticed that the bars are tapering toward the inside, so as to prevent the clogging by ashes or slack between them. In this way a perfect combustion of the coal takes place and the ashes which accumulate in the fire-place will be discharged therefrom upon the rotation of the grate at the end, and caused to drop down into the ash-pit below by the depending movement of the grate, as shown.

What I claim as my invention, and desire to 95 secure by Letters Patent, is—

1. A hollow revolving grate having spiral bars and spaces, in combination with the

ratchet and pawl, the frame B, journals o and p, and the shaft o', substantially as and for the purpose described.

2. A pivoted hollow cylindrical grate having spiral bars and spaces, and a pawl and ratchet, in combination with a rectangular grate provided with pivots, and bearings in which the pivots rest, and a sliding bar in suitable bearings, with a roller on the inner end

attached thereto, substantially as and for the purpose described.

In testimony whereof I affix my signature in presence of two witnesses.

HENRY BORN.
